UNITED STATES PATENT OFFICE.

ROBERT SUCZEK, OF PHILADELPHIA, PENNSYLVANIA, ASSIGNOR TO C. H. WHEELER MANUFACTURING COMPANY, OF PHILADELPHIA, PENNSYLVANIA, A CORPORATION OF PENNSYLVANIA.

METHOD OF AND APPARATUS FOR COMPRESSING FLUID.

Application filed January 16, 1919, Serial No. 271,362. Renewed May 9, 1923.

To all whom it may concern:

Be it known that I, ROBERT SUCZEK, a citizen of the Czecho-Slovak Republic, residing in the city and county of Philadelphia,

5 State of Pennsylvania, have invented certain new and useful Improvements in Methods of and Apparatus for Compressing Fluid, of which the following is a specification.

10 My invention relates to a method of and apparatus for compressing fluid, such as air, gas, vapor, or a mixture of them, by ejector action, that is, by the action of motive fluid, such as steam or other elastic fluid under pressure, which is allowed to expand and entrain the fluid to be compressed, the mixture of the fluids travelling at high velocity losing its kinetic energy and increasing in pressure. My invention relates more particularly to a method of and apparatus for compressing fluid in a plurality of stages by action thereon of motive fluid in one stage, the condensable fluid from that stage being condensed and the compressed fluid, as air, being acted upon in a later stage to further raise its pressure, as by further ejector action.

15 My invention resides in a method of compressing elastic fluid, as air, which consists in raising its pressure by ejector action of condensable motive fluid, as steam, passing the mixture of air and steam through a passage or a plurality of passages, as through a tube or a plurality of tubes, preferably so proportioned as to cause the mixture to pass therethrough at substantial velocity, condensing the steam from the mixture while so passing through the passage or passages, and subjecting the air to further compression by any suitable method, preferably by further ejector action.

20 My invention resides also in apparatus comprising an ejector delivering the motive fluid and compressed fluid, as steam and air, to a condenser comprising a passage or a plurality of passages, as a tube or plurality of tubes, through which the mixture of steam and air is passed, and means for cooling the exteriors of the passage or passages to cause condensation of the steam while passing therethrough. My invention comprehends also in combination with such ap-

paratus means for delivering the air delivered from the condenser to a further pump of any suitable type for further raising its 55 pressure, such pump being preferably, however, another ejector.

25 My invention resides in the method and apparatus hereinafter described.

30 For an illustration of one of many forms my apparatus may take, and for an understanding of my method, reference is to be had to the accompanying drawing, in which:

35 Fig. 1 is a vertical sectional view, some parts in elevation, through structure embodying my invention.

40 Fig. 2 is a sectional view taken on the line A—A of Fig. 1.

45 Fig. 3 is a sectional view taken on the line B—B of Fig. 1.

50 Referring to the drawing, E is an ejector of any suitable structure or type, and in the example here illustrated is a tubular ejector comprising the motive fluid expanding nozzles N, the tubular converging-diverging 75 diffuser D, and the suction chamber A having the suction port A¹ through which enters the air or other fluid to be compressed. Steam or other suitable motive fluid is supplied to the nozzles N through the pipe a 80 controlled by valve b and delivering into the chamber c with which the nozzles N communicate.

55 The box or chest B is divided into two compartments or chambers d and e by the 85 diaphragm or partition f. The chambers d and e have a wall formed by the plate or tube sheet g held between the box or chest B and one end of the condenser shell C. Integral with or attached to the tube sheet g 90 is the horizontally extending plate or baffle i terminating short of the right end of the condenser shell C. The plate i, as shown in

95 Fig. 3, divides the interior of the condenser shell into practically two halves or compartments. In these compartments is disposed a plurality of tubes j, each of which at its one end extends through the tube sheet g into

100 communication with the chamber d and at its other end extends through the tube sheet g into communication with the chamber e. These tubes are expanded or otherwise secured fluid-tight in the tube sheet g,

as well understood in the condenser art.

The tubes are of copper, brass or any other suitable material, preferably a good conductor of heat. The tubes *j* extend from the chamber *d* horizontally lengthwise of the shell *C* beyond the member *i* and then bend downwardly into the lower compartment and return horizontally into communication with the chamber *e*. Cooling water enters the lower compartment of the condenser shell through the passage *k* in the enlargement *h* on the shell *C*. It surrounds and cools the tubes *j* and flows toward the right through the lower compartment, then upwardly and to the left through the upper compartment and leaves by the passage *m* through a similar enlargement *h* on the upper side of the condenser shell *C*. The direction of flow of the cooling water is in both compartments counter to the flow within the tubes *j*.

In the chamber *e* is a vertically extending diaphragm or partition *n* which falls short of the partition *f*, leaving a passage *o* above its top edge. The partition *n* in effect divides the chamber *e* into the two compartments *p* and *q* between which there is a passage *r* through the lower end of the member *n*. With the bottom of the compartment *q* communicates the condensate outlet *s*, and with the upper part of the compartment *p* communicates the outlet *t* delivering air in divided streams into the passages *u* delivering into the suction chamber *A*² of a second ejector *E*¹, preferably and here shown as of a type producing a disk-shaped jet of motive fluid received into surrounding annular diffuser. The ejector *E*¹ may be of any suitable type, as a tubular ejector, but is preferably of a type disclosed in my U. S. Patent No. 1,282,595, dated October 22, 1918. In the ejector *E*¹ the nozzle structure *N*¹ receives motive fluid, as steam, from the chamber *v*, which receives it through the valve *w* connected to any suitable source of live or exhaust steam, the steam entering through the valve *w* being delivered both to the chamber *v* and to the pipe *x*. The nozzle structure *N*¹ expands the steam into a disk-shaped jet, which entrains air from the suction chamber *A*², the mixture being delivered into any suitable surrounding annular diffuser passage *D*¹, in which the pressure is raised and the mixture delivered into the surrounding discharge passage *x* having the discharge port *y*.

As described, the structure may be considered to consist of multi-stage ejector apparatus with an interstage condenser in which the mixture of steam and air from the first stage is passed through passages or tubes which are long as compared with their diameters. While I prefer an ejector in the second stage, my invention comprehends also the use in the second stage of any type of pump, as a reciprocating, rotary, en-

trainment, wet or dry or hydraulic air pump, or any other suitable type.

The mixture of air and steam, at higher pressure than the air entering at *A*¹, is delivered from the first stage diffuser through the passage *F* in box or chest *B* to the chamber *d* and thence passes through the tubes *j*. The total cross section of the passages of the tubes *j* is relatively small, whereby by utilizing part of the pressure imparted by the ejector *E* the mixture of steam and air from chamber *d* travels at relatively high velocity through them. By way of example merely, each tube *j* has a length ten or more times its internal diameter. This high velocity is of advantage in that it prevents collection of air upon the inner surfaces of the tubes, and prevents formation of air pockets, so that the heat in the mixture of air and steam is rapidly and readily transferred through the walls of the tubes to the surrounding cooling water entering at *k* and leaving at *m*.

As the mixture progresses through the tubes *j*, the steam is more and more completely condensed and is delivered as water or condensate into the compartment *q* of chamber *e*, and is withdrawn through or flows out of the condensate outlet *s*.

Because of progressive condensation of steam within the tubes *j* the volume available for occupancy by the air increases progressively from the inlet to the outlet of tubes *j*. Accordingly the air velocity diminishes from the entry to the outlet of the tubes. But notwithstanding this, the velocity of the air through the tubes is quite high, particularly soon after entering the tubes *j* from chamber *d*. Due to the high velocity of the fluid within the condenser tubes, there is a fall of pressure between chambers *d* and *e*, so that the pressure of the air leaving the diffuser *D* of the first stage ejector *E* is reduced by the time it reaches the chamber *e* in which, however, the pressure is materially higher than the suction pressure at *A*¹.

Notwithstanding this drop or loss in pressure in the tubes *j*, economy in total amount of motive fluid used in both stages *E* and *E*¹ is effected because of the condensation of the motive fluid from the first stage, which leaves only air to be compressed by the second stage pump or by the ejector *E*¹.

The air delivered by the tubes *j* into chamber *e* separates from the water delivered into said chamber from the condenser tubes *j* and passes over the partition or baffle *n* through the passage *o* into the compartment *p*, where any further water which separates from the air collects on the bottom of the compartment *p* and flows back into compartment *q* through the passage *r*, and passes out through the condensate passage *s*. The air passes from near the top of

compartment p through the passage t into the second stage pump or ejector, where it is further raised in pressure by any suitable mode or means, in the example illustrated 5 by an ejector, which delivers the air at outlet y at atmospheric pressure or any other desirable pressure higher than the suction pressure A^1 .

My apparatus and method may be employed to compress air or the like from any desired pressure at, below or above atmospheric pressure to a higher pressure. My apparatus and method may be employed in any suitable environment, but finds a large 10 part of its application to removal of air or uncondensable vapors from condensers of steam from turbines, engines or other sources.

For example, it may be desired to maintain in the condenser a vacuum of 29 inches, referred to the 30 inch barometer. This means that the air enters the suction port A^1 of the first stage at a pressure of practically 1 inch mercury absolute; and is delivered at y at atmospheric pressure or at a pressure more or less above or below atmospheric pressure, depending upon the region into which the air is discharged from the port y . When so raised to atmospheric pressure, it has attained a pressure of practically 30 inches of mercury, and the total 20 ratio of compression over both stages in series is practically 30.

The ratio of compression in the first stage 30 ejector E as compared to the ratio of compression in the second stage pump or ejector E^1 may be anything desired. For example, the ratio of compression in the first stage may be smaller than the ratio of compression in the second stage pump of any suitable character, whether operating upon the 40 ejector principle or some other principle. Or the ratio of compression in the first stage may be and preferably is higher than in the second stage, particularly when the second stage pump is an ejector either of the type indicated or of any other suitable type. In such case a relatively great amount of motive fluid is employed in the first stage and 50 performs a relatively large part of the total work in compressing the air to a relatively high pressure. This large amount of motive fluid, however, is condensed out in the interstage condenser, leaving the second stage to effect further compression of the air with 60 relatively smaller compression ratio and smaller consumption of motive fluid. The motive fluid consumption in the second stage is relatively small because not only is the first stage motive fluid absent, but the air has theretofore been compressed through a large part of its total range of compression.

Furthermore, whatever the type of second stage pump, whether or not an ejector, 65 the fact that the air as it is discharged

from the interstage condenser has been cooled, its density is greater, that is, its volume is less, requiring less work on the part of the second stage pump or ejector.

While in the example of the apparatus 70 embodying my invention as illustrated in the drawing the ejectors are disposed one vertically above the other, with the condenser extending in a substantially horizontal direction, it will be understood that my invention 75 comprehends structure whose parts are otherwise disposed with respect to each other.

However, the separation between the first 80 and second stage ejectors, or between the first stage ejector and the second stage pump, is less where the condenser tubes extend laterally as illustrated. And this arrangement of the condenser tubes is preferred 85 over that where, also comprehended within my invention, they extend in the same general direction as the direction of alignment between the first stage ejector and the second stage pump or ejector. Where the first stage ejector and the second stage pump or 90 ejector are to be relatively close together as measured vertically, employment of vertical condenser tubes would necessitate, in order to reduce the over-all vertical height of the apparatus, employment of relatively short 95 condenser tubes which, though comprehended within my invention, are not a preferred structure. Relatively long passage or

passages in the condenser with small total cross sectional area is or are preferred in 100 order that, as previously explained, the velocity of the fluid through the condenser tubes shall be high enough to prevent collection of air, or formation of air pockets, or to prevent air binding and to facilitate 105 rapid heat transfer into the cooling water. By the employment of such long passage or 110 passages not only is the velocity beneficially high, as described, but the time of contact with the water cooled walls of the tube or tubes is lengthened, contributing to complete condensation of vapors from the first stage ejector.

In accordance with my method and apparatus, the mixture of steam and air from 115 the first stage is passed to the second stage pump or ejector while confined within the condenser tubes, the cooling water flowing around the tubes in the interspace between them, as distinguished from the case where 120 the mixture of fluids from the first stage is delivered into an interstage condenser of the jet type or the type in which the cooling water flows through condenser tubes, and the mixture from the first stage contacts the 125 outer surfaces of such tubes in the interspace between them. In this latter type of structure air pockets may be formed, that is, the interstage condenser may become air-bound, reducing the effective cooling surface 130

of the condenser and in some cases causing localized accumulation of air pressure which may cause a backward impulse of pressure towards or through the first stage ejector and which, if sufficiently powerful, may disturb the operation conditions or even break the vacuum.

While I have herein illustrated the passage or passages *j* between the ejector and the second stage pump or ejectors of circular cross section, it will be understood that my invention is in no wise limited to such shape of cross section, and that any other suitable cross section may be employed, as for example rectangular, triangular, etc. In such case again it is preferred that the length of the passage shall be great as compared to the smaller or smallest dimension entering into the determination of the cross section. For example, if the passage have a cross section which is a rectangle whose length is twelve times its width, the length of the passage is preferably ten or more times the smaller dimension, to wit, the width.

It will therefore be understood in connection with the appended claims that the "diameter" of passage therein referred to is its internal diameter if of circular cross section, and when of other than circular cross section the term diameter refers to the diameter of the largest circle which can be inscribed within the figure of the cross section. Thus, in the foregoing example the diameter of the rectangular cross section is its width or smaller dimension.

The passage or passages *j* is or are preferably of such length as compared to cross section that the mixture from the first stage ejector moves rapidly therethrough under a suitably great difference of pressure between the entry to and exit from said passage or passages.

What I claim is:

1. The method of compressing an uncondensable elastic fluid in a plurality of stages, which consists in ejecting the same by condensable motive fluid to a higher pressure, passing the mixture in divided streams at high velocity through a plurality of continuous passages which are long as compared to their diameter, extracting heat from the walls of said passages, condensing said motive fluid, and ejecting the uncondensed fluid by motive fluid to a higher pressure, the ratio of compression in the first stage being higher than the ratio of compression in the later stage.

2. The method of compressing an elastic fluid in stages, which consists in ejecting the same by motive fluid to a higher pressure, passing the mixture through a plurality of continuous passages which are long compared with their diameter, extracting heat from the walls of said passages to condense said motive fluid, ejecting the elastic fluid

by motive fluid to a higher pressure, and maintaining a difference in pressure between the ends of said passages sufficient to cause said mixture to pass therethrough at high velocity.

3. Combined ejector-condenser structure comprising ejectors, an interstage condenser comprising a plurality of continuous tubes extending forwardly and backwardly and connecting the discharge of one ejector with the suction of another ejector, and a baffle between the forwardly and backwardly extending portions of said tubes.

4. Multi-stage ejector-condenser structure comprising an ejector, a chamber into which it discharges, a second chamber, a plurality of continuous tubes connecting said chambers, and a second ejector having its suction connected to said second chamber.

5. Multi-stage ejector-condenser structure comprising an ejector, a condenser comprising a continuous passage connected to the discharge of said ejector, means for extracting heat from the walls of said passage, and a second ejector comprising nozzle structure for producing a disk-shaped jet and a surrounding annular diffuser receiving fluid from said passage.

6. Multi-stage ejector-condenser structure comprising a tubular ejector, an ejector associated in series therewith and comprising nozzle structure for producing a disk-shaped jet and a surrounding annular diffuser, and a condenser disposed between said ejectors and comprising a plurality of continuous passages into which said first ejector discharges and from which said second ejector receives elastic fluid.

7. Multi-stage ejector-condenser structure comprising an ejector, a condenser comprising a plurality of continuous passages extending forwardly and backwardly and connecting the discharge of said ejector with the suction of another ejector, a baffle disposed between the forwardly and backwardly extending portions of said passages, a jacket surrounding said passages, and means for passing a cooling medium into said jacket adjacent the second named ejector and out of said jacket adjacent said first named ejector.

8. Combined ejector-condenser structure comprising an ejector and a pump, a chamber receiving the discharge from said ejector, a second chamber having a partition therein dividing the same into compartments, a connection from one of said compartments to said pump, a liquid discharge from another of said compartments, a plurality of continuous tubes connecting said first named chamber with said last named compartment, and means for extracting heat from the walls of said tube.

9. Multi-stage ejector-condenser structure comprising an ejector, a chamber connected

- to the discharge of said ejector, a second chamber, a wall in said second chamber dividing the same into compartments, passages through said wall connecting said compartments, a second ejector having its suction connected to one of said compartments, and a plurality of U-shaped tubes connecting another of said compartments with said first named chamber.
- 10 10. Fluid compressing apparatus comprising a chamber, an ejector delivering to said chamber, a second ejector, a second chamber, a wall in said second chamber dividing the same into two compartments, 15 passages through said wall connecting the same at top and bottom, a passage connecting one of said compartments with said second ejector, a liquid drain connected to the other of said compartments, and an inter- 20 stage condenser comprising a plurality of continuous passages connecting said first
- named chamber with said last named compartment.
11. Multi-stage ejector-condenser structure comprising a chamber, an ejector 25 mounted on said chamber and delivering thereto, a second chamber, a wall in said second chamber dividing the same into two compartments, passages through said wall connecting the same at top and bottom, a 30 second ejector supported upon said second chamber and communicating with one of said compartments, a liquid drain connected to the other of said compartments, a plurality of continuous tubes connecting said first named chamber with said other of said compartments, and a shell surrounding said tubes. 35

In testimony whereof I have hereunto affixed my signature this 15th day of January, 1919. 40

ROBERT SUCZEK.
